[57] CLAIM

The ornamental design for a cake top ornament, substantially as shown and described.

DESCRIPTION

FIG. 1 is a perspective view of a cake top ornament embodying my new design.

FIG. 2 is a top plan view of the cake top ornament of FIG. 1.

FIG. 3 is a side view of the cake top ornament of FIG. 1.

The bottom of the cake top ornament is plain.

FIG. 2.

FIG. 3.
